ABSTRACT OF THE DISCLOSURE

An electron beam-plasma amplifier containing an electron gun and collector for forming an electron beam and a cylindrical magnet surrounding said beam for imparting transverse velocity components to the charged particles in the device. Signals to be amplified are coupled into and out of the device at a frequency that is a multiple of the plasma cyclotron frequency.

This invention relates to electron stream apparatus for generating and amplifying electromagnetic waves, and more particularly to such devices capable of reliably operating at frequencies much higher than the frequencies at which currently known electron stream devices operate.

There is at present a considerable effort being devoted to develop efficient and relatively simple devices for generating and amplifying electric field waves in the higher ranges of the microwave frequency spectrum, and in the millimeter and submillimeter wavelength ranges. Conventional oscillators and amplifiers such as the diverse types of magnetrons, klystrons and electron beam-traveling wave interaction devices have physical dimensions that are of the order of wavelengths of the waves that they generate or amplify. At very high frequencies these devices are so small in size that they are extremely difficult to manufacture, are costly, and the power of the waves that they can generate and amplify is quite low. Some consideration has been given to the generation and amplification of electromagnetic waves by the use of devices that employ a stream of electrons that passes through an ionized gas, i.e., a plasma. It was hoped that in this way the limitations on size and tolerances of dimensions could be avoided. It has been found by most investigators, however, that in order for the beam-plasma devices to function in a practically useful way, the plasma density must be high, and therefore so must be the strength of the magnetic field that confines the plasma and the electron beam. This requires large, heavy, and expensive magnets. Furthermore, the axial phase velocities of the interacting beam and plasma waves are low so that special slow wave propagating circuits, and associated coupling means, must be provided.

In most prior investigative work involving electron stream and electric field wave interactions in a gas plasma, and in the presence of a steady axial magnetic field, it was assumed that beam electrons had only axially directed velocities and the conventional negative-energy slow space charge beam wave or the slow fundamental cyclotron wave interacted with a plasma wave that fell within one of the two propagating bands of the plasma, i.e., one frequency band being from 0 to ω_c or ω_p whichever was the smaller, and the second band being from the larger of ω_c or ω_p to $(\omega_c^2 + \omega_p^2)^{1/2}$, where ω_c is the radian cyclotron frequency and is equal to $e/m B$, and ω_p is the plasma radian plasma frequency and is equal to

$$\left(\frac{n_p e^2}{m \epsilon_0} \right)^{1/2}$$

where e/m is the charge to mass ratio of an electron, B is the axial D.C. magnetic field strength, n_p is the plasma electron density, and ϵ_0 is the dielectric constant of free space.

5 In devices whose operations depend upon interactions of the types just described, it is apparent that the maximum possible frequency of operation is in the frequency range $(\omega_c^2 + \omega_p^2)^{1/2}$, and because this frequency is a function of the plasma electron density n_p and the axial magnetic field strength B , it is impractical, in terms of apparatus to generate or amplify waves much above a frequency of several gigacycles (cycles $\times 10^9$).

Some investigators have reported observing radiations in the frequency range of multiple harmonics of the cyclotron frequency from beam-plasma devices, but to date they have been little more than laboratory curiosities and no satisfactory explanation has been offered for them.

10 It therefore is an object of this invention to provide wave-propagating electron stream apparatus for generating and amplifying electric field waves at, and above, the higher microwave frequencies.

15 Another object of this invention is to operate a magnetically-focussed electron beam device in such a manner that the electrons of the beam have sufficient velocity in the direction transverse to the beam axis to give rise to negative energy transverse electrostatic beam waves in the regions of integral multiples of the beam cyclotron frequency, these waves coupling to and amplifying transverse electrostatic plasma waves at comparable frequencies and phase velocities.

20 A further object of this invention is to provide an electron beam-electric field interaction device in which one of the interacting waves is an electrostatic beam wave at a frequency near an integral multiple of the beam cyclotron frequency and which has a high phase velocity in a direction parallel to the beam axis.

25 In accordance with one embodiment of the present invention, means are provided for producing an electron beam that flows along an axis through a gas plasma. A unidirectional magnetic field is directed along the axis and confines the electron beam. An essential characteristic of the beam is that the electrons must have a large component of velocity in a direction transverse to the beam axis, the electrons thereby executing a spiraling motion about magnetic field lines as they move axially along the beam. Under these conditions there exists on the beam a family of high frequency transverse electrostatic waves having respective positive energy and negative energy waves in the vicinity of each higher harmonic of the cyclotron frequency. The plasma electrons also must have large rotational energies about the magnetic field lines so that the plasma supports a family of high frequency transverse electrostatic waves which also fall in the vicinity of the higher cyclotron frequency harmonics. The signal to be amplified is at a frequency in the vicinity of one of the higher harmonics of the cyclotron frequency and is coupled to electrostatic waves in the plasma at a corresponding frequency and having a phase velocity that is substantially synchronous with that of the beam waves. Certain

30 parameters of the beams and plasma are judiciously proportioned to assure stable propagation of the respective waves. Interaction takes place between the beam and plasma waves with the negative energy beam wave giving up energy to the plasma wave and thereby amplifying it. Means are provided for coupling the amplified wave from the plasma. The interacting waves in the beam-plasma system are characterized by having a high axial phase velocity much higher than the axial velocity of the beam so that the input and output coupling means may be higher

35 phase velocity circuits and transmission lines, thus obviating the need for special slow wave circuits and cou-

pling means as conventionally required in present day electron beam-wave interaction devices.

The present invention will be described in connection with the accompanying drawings wherein:

FIG. 1 is a simplified sketch illustrating the type of electron motion that is required in the beam employed in devices operating in accordance with the present invention;

FIG. 2 is a graph of the plasma dispersion function Z which appears in the equation for the dielectric constant of a beam and a plasma;

FIGS. 3 and 4 are dispersion curves of the beam and plasma, respectively, which are proportioned in accordance with the teachings of this invention; and

FIGS. 5, 6 and 7 are simplified illustrations of three different beam-plasma devices that are constructed to operate in accordance with the teaching of the present invention.

Before proceeding with a detailed description of the apparatus for carrying out the invention, it is believed that it will be helpful to first present an explanation of the characteristics and critical features of the beam and plasma which give rise to the generation and amplification of the transverse electrostatic waves at frequencies in the regions near multiple harmonics of the beam cyclotron frequency. An essential feature for devices operating in accordance with this invention is that the electrons of the beam which traverse the plasma must have substantial speeds in a direction transverse to the axially directed steady magnetic focussing field B . It further is assumed that the axial electrostatic space charge fields are neutralized by the ions of the plasma that surrounds the beams. The beam electrons execute a spiraling motion about the axially directed steady magnetic field lines, as represented quite generally in FIG. 1, wherein the encircled crosses represent magnetic field lines directed into the plane of the paper and the spiraling electrons are represented by dots on a respective orbit. The spiraling electrons give rise to transverse electrostatic waves having short transverse wavelengths

$\lambda_{\perp}$

as illustrated for two of the electrons in FIG. 1, these transverse electrostatic waves being of importance in the understanding of the present explanation. The character of these waves may be explored by investigating the electrostatic dispersion equation for the beam, this being derived from the equation of the longitudinal dielectric constant of the beam. The equation for the longitudinal dielectric constant of a beam is known and may be written as follows:

$$K(\omega, k) = 1 +$$

$$\frac{\omega_b^2}{k^2} \sum_{n=-\infty}^{\infty} \int_{-\infty}^{\infty} dv_{\perp} v_{\perp} \int_{-\infty}^{\infty} dv_{\parallel} \frac{2\pi J_n^2 \left(\frac{k_{\perp} v_{\perp}}{\omega_c} \right)}{(\omega - k_{\parallel} v_{\parallel} - n\omega_0)} \left[\frac{n\omega_0}{v_{\perp}} \frac{\partial}{\partial v_{\perp}} + k_{\parallel} \frac{\partial}{\partial v_{\parallel}} \right] f_o(v_{\perp}, v_{\parallel}) \quad (1)$$

where ω_b and ω_c are the radian beam plasma and cyclotron frequencies, respectively, ω is the radian frequency of the waves to be amplified, $v_{\perp}$ is the transverse velocity component of beam electrons, $k_{\perp}$ and $k_{\parallel}$ are transverse and longitudinal wave numbers, respectively, which are related to k by the relationship

$$k^2 = k_{\perp}^2 + k_{\parallel}^2$$

k being defined as $2\pi/\lambda$, λ being wavelength, J_n is the Bessel function of argument

$$\frac{k_{\perp} v_{\perp}}{\omega_c}$$

n is an integer, and

$$f_o(v_{\perp} v_{\parallel})$$

is the velocity distribution function of the beam electrons. Considering that the beam electrons have a spread in axial and perpendicular velocity as a result of the cathode temperature as well as the spread introduced by the generation of the perpendicular electron motion, the velocity distribution function of the beam, assumed to be Gaussian or Maxwellian, may be given as

$$f_o(v_{\perp}, v_{\parallel}) = \frac{1}{(2\pi)^3/2v_t^2 u_t^2} \exp - \frac{1}{2} \left[\left(\frac{v_{\perp}}{v_t} \right)^2 + \left(\frac{v_{\parallel} - u}{u_t} \right)^2 \right] \quad (2)$$

where u is the beam axial drift velocity, u_t is the R.M.S. thermal velocity of the electrons along the steady magnetic field, and v_t is the R.M.S. velocity across the field and in general is different from u_t . By substituting Equation 2 into Equation 1, Equation 1 reduces to the form

$$K = 1 + \frac{\omega_b^2}{k^2 u_t^2} \left[1 + \sum_{n=-\infty}^{\infty} I_n(\lambda) e^{-\lambda} \left[\frac{\bar{\omega} - n\omega_0(1-\beta)}{\sqrt{2k u_t}} \right] Z(\xi_n) \right] \quad (3)$$

where

$$\bar{\omega} = \omega - k_{\parallel} u, \text{ and } Z(\xi_n)$$

is the plasma dispersion function and may be defined in general terms as equal to

$$Z(\xi) = \frac{1}{\sqrt{\pi}} \int_{-\infty}^{\infty} \frac{dx}{x - \xi} e^{-x^2} \quad (4a)$$

or

$$Z(\xi) = 2i \exp(-\xi^2) \int_{-\infty}^{i\xi} \exp(-t^2) dt \quad (4b)$$

$$\xi_n = \frac{\omega - n\omega_0 - k_{\parallel} u}{\sqrt{2k u_t}}, \quad \beta = \frac{u_t^2}{v_t^2}$$

and

$$I_n(\lambda)$$

is the modified Bessel function of the first kind of imaginary argument, the argument λ being defined as

$$\lambda = \left(\frac{k_{\perp} v_t}{\omega_c} \right)^2$$

50 The plasma dispersion function $Z(\xi_n)$, and the term ξ_n are extensively defined and evaluated in the book The Plasma Dispersion Function, by B. D. Fried and S. D. Conte, published by Academic Press, New York and London, copyright 1961. The variable ξ_n has both real and 55 imaginary parts, i.e., $\xi = x + iy$, and has the significance of the ratio of phase velocity of a wave to some thermal velocity. The existence of the imaginary part of ξ indicates that the dispersion relationship, presently to be derived, will exhibit wave damping, the damping for $n=0$ being known as Landau damping while the wave damping for frequencies in the neighborhood of a cyclotron harmonic frequency $n\omega_c$ is known as collisionless cyclotron damping. The real and imaginary parts of Z are plotted in FIG. 2.

60 It may be seen in FIG. 2 that for values of ξ around 1.4 i.e. $\sqrt{2}$, the magnitude of the imaginary part that gives rise to wave damping becomes quite small. Therefore, evaluating the equation for the dielectric constant with the condition $\xi_n \gg 1$, and assuming $v_t \gg u_t$, Equation 3 becomes

$$K_b = 1 -$$

$$\frac{\omega_b^2}{k^2 u_t^2} \sum_{n=-\infty}^{\infty} I_n(\lambda) e^{-\lambda} \left[\frac{k_{\parallel}^2 v_t^2}{(\bar{\omega} - n\omega_0)^2} + \frac{n\omega_0}{(\bar{\omega} - n\omega_0)} \right] \quad (5)$$

Setting Equation 5 equal to zero gives the dispersion equation for a low density beam ($\omega_b \ll \omega_c$) as approximately

$$\frac{k_{\parallel}^2}{k_{\perp}^2} \approx -\frac{(\bar{\omega} - m\omega_c)X\bar{\omega} - m\omega_c - \omega_b^2 I_m(\lambda) \frac{\omega_c}{\lambda \omega_c}}{(\bar{\omega} - m\omega_c)^2 - \omega_b^2 I_m(\lambda) e^{-\lambda}} \quad (6)$$

This dispersion relationship for the assumed beam is plotted in FIG. 3, wherein the regions where collisionless wave damping is significant appears as the cross-hatched regions of the curves.

By considering FIG. 2 and the equation that defines ξ_n above, it may be seen that the wave damping is introduced by a spread in axial velocity, but not in perpendicular speed. Further, this undesirable damping may be avoided when the relationship

$$\frac{\bar{\omega} - m\omega_c}{\sqrt{2} k_{\parallel} u_t} \gg 1 \quad (7)$$

is approximately satisfied.

The minimum ratio of transverse to longitudinal beam electron velocities to assure that relatively undamped transverse electrostatic waves will propagate on the beam may be estimated by substituting the quantity

$$k_{\parallel} u_t \text{ for } \bar{\omega} - m\omega_c \quad (25)$$

in Equation 6. For the m th mode, and using $\frac{1}{4}m$ as the maximum value of $I_m(\lambda) e^{-\lambda}$ (which occurs when

$$\left(\lambda = \frac{k_{\perp}^2 v_t^2}{\omega_c^2} \approx m^2 \right) \quad (30)$$

the minimum ratio may be expressed as

$$\frac{v_t^2}{u_t^2} > 4m \frac{\omega_c^2}{\omega_b^2} \quad (8)$$

Now considering further the beam wave dispersion curves of FIG. 3, it is seen that the beam will propagate two undamped waves in the neighborhood of each cyclotron harmonic frequency. By applying an extension of the well known Chu kinetic power theorem it can be shown that the upper frequency curve, $\omega > m\omega_c$, of each pair carries positive energy and the lower frequency curve, $\omega < m\omega_c$, of each pair carries negative energy. Should the negative energy beam wave couple to a positive energy beam wave, the positive energy wave will grow in amplitude due to energy transfer from the negative energy wave, and the beam itself will become unstable. For devices intended for use as oscillators this would be required, but for a device intended for use as an amplifier of an applied external signal, this condition must be avoided. At sufficiently high electron densities n_b , the positive energy wave for the m th mode will intersect the negative energy wave of the $m+1$ th mode, thereby giving rise to the afore-described beam instability. The critical or maximum electron beam density which will avoid these instabilities may be estimated by setting the asymptotes for the negative energy wave at the $m+1$ th cyclotron harmonic equal to the positive energy wave at the m th cyclotron harmonic, which for the beam described in Equation 2 is

$$\omega_{\text{berit.}}^2 < \frac{\omega_c^2}{[I_m(\lambda) + I_{m+1}(\lambda)] e^{-\lambda}} \quad (9)$$

An approximate evaluation for Equation 9 is

$$\omega_{\text{berit.}}^2 < 8m\omega_c^2 \text{ for } m \gg 1 \quad (10)$$

Having thus shown that a beam whose electrons have significant transverse velocity v_t will stably propagate transverse electrostatic waves at frequencies in the region of cyclotron harmonic frequencies $m\omega_c$, it now will be shown that a "warm" gas plasma exhibits similar characteristics, a warm plasma being one in which the plasma electrons have transverse and longitudinal motion, but no defined drift velocity along the magnetic field. The plasma electron velocity relationships thus may be recited

as $v_t^2 = u_t^2$, and $u = 0$. Because the dielectric constant equation for the gas plasma also includes the plasma dispersion function Z of Equation 4, the relationship

$$\omega - m\omega_c > \sqrt{2} k_{\parallel} u_t$$

must again hold true in order to avoid collisionless wave damping in the warm gas plasma. With these basic relationships defined, the longitudinal dielectric constant of the warm plasma may be expressed as

$$K_p = 1 - \frac{\omega_p^2}{k_{\perp}^2 u_t^2} \sum_{n=-\infty}^{\infty} I_n(\lambda) e^{-\lambda} \frac{n\omega_c}{\omega - n\omega_c} \quad (11)$$

where ω_p is the radian plasma frequency of the warm plasma and all other quantities in the expression have the same definitions as given above, except that here they now refer to the warm plasma rather than the beam. Equation 11 is solved for frequencies in the neighborhood of $\omega = m\omega_c$ by removal of the m th term and evaluating all the other terms at $\omega = m\omega_c$, with the assumption that

$$k^2 \approx k_{\perp}^2 \gg k_{\parallel}^2$$

thereby giving the following for the dispersion relationship of the warm gas plasma:

$$\frac{\omega - m\omega_c}{\omega_c} = \frac{m \frac{\omega_p^2}{\lambda} I_m(\lambda) e^{-\lambda}}{\omega_c^2 - \frac{\omega_p^2}{\lambda} \sum_{n+m}^{\infty} I_n(\lambda) e^{-\lambda} \left(\frac{n}{m-n} \right)} \quad (12)$$

FIG. 4 is a plot of Equation 12 for several different values of ω_p^2/ω_c^2 , and for a limited range of ω/ω_c . The curves of FIG. 4 show generally that the frequencies of the plasma waves may be on either side of the harmonics. The plasma electron densities, i.e., ω_p , that give upper hybrid solutions between any two harmonics form the boundaries between two density regions. At higher plasma densities the curves approach the higher harmonics as λ approaches zero. At lower densities they approach the lower harmonics. All the curves have the common feature that they approach the cyclotron harmonics on the high frequency side at large values of λ . The curves of FIG. 4 are positive energy curves.

It may be seen from the above explanation that both the electron beam and the warm plasma will support transverse electrostatic waves at high frequencies in the ranges of multiple harmonics of the cyclotron frequency. Therefore, by proportioning the parameters of the beam and the warm plasma in accordance with the above teachings it is possible to produce a negative energy beam wave and a positive energy plasma wave which have substantially the same phase velocities at a selected frequency in a region of a multiple cyclotron harmonic frequency, thereby providing the necessary conditions that are required for amplification of an applied signal at the selected frequency. In amplifying devices operating in this manner, input coupling means are provided for coupling electromagnetic waves at the selected frequency to the positive energy electrostatic plasma waves, and similarly, output coupling means are provided for coupling the amplified electrostatic waves to external wave propagating means in which the waves propagate as electromagnetic waves.

Although the above development of the transverse electrostatic beam waves assumed that the beam electrons had a Maxwellian velocity distribution function, it will be understood that in an actual beam of the type under consideration, this assumption will not be strictly true. However, the departure in practice from this assumption actually will be more favorable to the generation of the transverse electrostatic waves with which this invention is concerned.

FIG. 5 is a simplified illustration of a beam-plasma device that functions as an amplifier in accordance with the principals explained above. As emphasized in the above discussion, it is a necessary requirement that the beam electrons have high speeds in a direction transverse

to the beam axis, and in the embodiment of the invention illustrated in FIG. 5 this is accomplished by the use of a shielded electron gun 10 which produces a beam of electrons which enters the longitudinally directed magnetic focussing field at a region where the magnetic field lines have radially directed components, thereby imparting a spiraling motion to the electrons. Electron gun 10 may be of the type described in U.S. Patent 2,707,758, issued May 3, 1955 to C. C. Wang and assigned to applicant's assignee. The gun is comprised of an electron emissive surface 11 and an accelerating anode 12 which produces a confined stream of electrons which traverses the length of a vacuum tight cylinder 14 and which is terminated in collector electrode 15. Cylinder 17 and an annular member 18, both of magnetic material, shield the gun from the magnetic focusing field which is produced by a longitudinally-extending electromagnet 20. Annular member 18 serves as a pole piece to cause the lines of magnetic flux to curve radially outwardly in the region where the beam enters the magnetic field, thereby producing the radial components of magnetic field which impart the transverse component of velocity to the beam electrons. Annular members 21 and 22 are disposed at each end of electromagnet 20 to complete the magnetic circuit.

Cylinder 14 is made of a low loss dielectric material such as glass or quartz and is provided with a port 25 through which an ionizable gas such as cesium, for example, may be admitted, the port then being pinched off when a desired gas pressure, has been achieved within the interior of the device.

Disposed about the dielectric cylinder 14 is an input resonant cavity 27 and an output resonant cavity 28. Cylinders of conductive material 30, 31 and 32 surround the dielectric cylinder 14 in the regions at the ends of cavities 28 and 29 and in the region therebetween so as to provide a conductive boundary about the cylinder 14. Signals to be amplified at a frequency near a multiple harmonic frequency are coupled through the coaxial coupler 33 into the input cavity 27, and after amplification are coupled from output cavity 28 by a similar coaxial coupler 34.

Because the beam waves and the plasma waves with which we are concerned are electrostatic waves whose electric fields extend transversely to the beam axis, resonant cavities 27 and 28 must resonate in a mode which also has transverse electric fields in order that the input and output electromagnetic waves may couple to and from the desired electrostatic waves of the beam and plasma. As an example, resonant cavities 27 and 38 may resonate in the TE_{111} mode, although any TE_{in1} mode should be satisfactory.

As pointed out in the above development, certain critical parameters must be established in the beam and in the plasma in order that the stable transverse electrostatic waves may propagate on the beam and plasma. For example, the temperature of cathode 11, the potential of accelerating anode 12, and the strength of the magnetic focusing field B provided by electromagnet 20 are proportioned so that the relationships expressed in Equations 7, 8 and 10 are satisfied for the electron beam. Similarly, with regard to the warm gas plasma, the relationships $k_{\perp} > k_{||}$, and $\omega - m\omega_c > \sqrt{2}k_{||}u_t$ are satisfied by properly proportioning the plasma electron temperature and electron density in accordance with the above Equations 11 and 12 so that the desired plasma waves will propagate with the desired phase velocity in the frequency range $m\omega_c - k_{||}u$ where the negative energy beam wave also is present.

One of the advantageous features of achieving the amplification by means of interaction of the transverse electrostatic beam-plasma waves at the higher harmonic frequencies is that low density beams and plasmas may be employed. This means that lower magnetic field strengths may be used for the longitudinal magnetic focusing field, thus minimizing the size, weight, and power requirements

of the magnetic field source. Another important advantage arising in devices operated in accordance with the present invention is that the axial wave number $k_{||}$ of the beam and plasma waves must be relatively small in order to avoid collisionless wave damping, as explained in connection with the discussion of the plasma dispersion function Z (ξ). Since the axial wave number $k_{||}$ is inversely related to the axial phase velocity $v_{p||}$ of the waves, this means that the phase velocity of the waves that enter into coupling relationship must be very high, and in practice this velocity is higher than the beam drift velocity v_d . This then means that slow wave propagating circuits are not necessary to couple the waves into or out of the plasma-beam system nor are they necessary in the interaction region of the device. Consequently, conventional electromagnetic wave transmission lines having high phase velocities may be employed throughout, thereby simplifying the design and the manufacture of the devices.

In the above embodiment of the invention it is contemplated that the gas contained within dielectric cylinder 14 will be ionized due to the collision of the beam electrons with the atoms or molecules of the ionizable gas that is employed. Although this method for generating plasma is presently preferred because of its simplicity, it should be understood that other methods for generating the plasma may also be employed, if so desired. For example, the plasma may be generated by means of a separate arc or spark discharge within the gas tube or by means of surface ionization in which an ionizable gas impinges upon a hot cathode of a material whose work function is higher than that of the gas. Further, the plasma temperature may be established and maintained by additional means, if necessary, such as heating with an electric field at the cyclotron frequency, or by means of passing a D.C. current through some portion of the plasma.

An alternative embodiment of the invention is illustrated in FIG. 6 in which a hollow spiraling electron beam 40 is employed in place of the solid electron beam 10 of the device illustrated in FIG. 5. The hollow spiraling beam is produced by means of an electron gun 41 which is comprised of a cylindrically shaped yoke member 43 which has an opening 44 at its left end, and a central rod 45 is centrally positioned within the opening 44 and joins the yoke member 43 at its opposite end. The yoke 43 and the center rod 45 are made of a magnetic material and a magnetizing coil 48 is wound about the center post 45 so as to establish a magnetic north pole at the right end of center post 45 and a south magnetic pole at the inner periphery of the open end of yoke 43. In this manner radially-directed flux lines extend across the open end of the gun. An electron emissive cathode 50 is positioned within the yoke 43 and about the center post 45 so as to emit a tubular stream of electrons. When these electrons pass through an accelerating anode 51 and the radially-directed magnetic flux lines at the open end of the gun structure, a transversely directed force is exerted on the electrons thereby causing them to spiral about the center axis of the tube to establish the hollow electron beam. A hollow conductive envelope 52 is secured to yoke member 43 in a vacuum tight manner and is secured at its opposite end in a similar manner to the beam collector electrode 54. A nib 55 is provided in conductive envelope 52 to permit the ionizable gas to be pumped into the device. The electromagnetic waves are coupled into the beam-plasma interaction regions by means of a coaxial line coupler 56 which has a center probe 57 extending into the interior of the device. In a similar manner an output coaxial line coupler 58 having an inner probe 59 provides an output coupler for the device. An electromagnet 60 surrounds the conductive envelope 52 and establishes the longitudinal magnetic field B for confining the beam and the plasma. The operating parameters for the beam and plasma are established in accordance with the above teachings so as to achieve the desired interaction between a negative energy beam wave

and a positive energy plasma wave whereby the externally applied signals at a frequency near a multiple harmonic of the cyclotron frequency are coupled to a transverse electrostatic wave supported by the plasma, this wave then being amplified by the transverse electrostatic negative energy beam wave at the corresponding frequency.

FIG. 7 is another embodiment of the present invention, this device being illustrated as a wave-wave type of amplifier, a solid beam of electrons is produced by the shielded electron gun 70 which may be the same type as described in connection with the device of FIG. 5. A permanent magnet 71 produces a magnetic field B that extends longitudinally in its central region and extends radially outward at its end regions. Upon entering the magnetic field B, the beam electrons are acted upon by a transversely directed force to cause them to assume a spiraling motion. The beam is collected at the right end of the tube by the collector electrode 72 after having passed through the plasma region 73.

Input waves at a frequency near a beam cyclotron harmonic frequency are coupled to a transverse electrostatic beam wave by means of the input coupler 75. Coupler 75 is comprised of two sets of three concentric cylinders which are fashioned from thin sheets of conductive material such as copper. The beam passes through the cylinders of each pair and has negligible intercept because of the thinness of the material from which the cylinders are made. The cylinders are spaced apart substantially an odd multiple of a half waveguide wavelength of the waveguide 84. Each set of cylinders of coupler 75 is excited in such a manner as to set up a transverse electric field of the waves to be amplified, and the two sets of cylinders are excited in phase opposition. That is, the signal to be amplified is split in phase by apparatus such as a T-junction, not illustrated, and the (+) phase component is coupled by means of a coaxial line coupler 77 to the outermost and innermost cylinders of the first set of cylinders, and by means of coaxial line coupler 78 to the center cylinder of the second set. The (-) phase component of the signal to be amplified is coupled by means of coaxial line coupler 79 to the center cylinder of the first set, and via coupler 80 to the outermost and innermost cylinders of the second set.

As discussed previously, the parameters of the beam and the magnetic focusing field B are proportioned so that a transverse electrostatic wave propagates on the beam at a frequency near a harmonic of the beam cyclotron frequency, this frequency being substantially equal to the frequency of the input waves to be amplified. With this condition prevailing, the beam passes through the transverse electric fields of input coupler 75 and the waves to be amplified are coupled to the beam. An ionizable medium such as cesium gas, as an example, is contained within a low loss dielectric tube 82, and the plasma temperature and electron density are proportioned as described above so that the plasma supports the type of waves illustrated in FIG. 4, one of these waves falling within the range of the frequency of the waves to be amplified. Beam waves and plasma waves then couple together to give rise to amplification within the plasma region 73.

In this embodiment of the invention, the dielectric tube 82 is surrounded by a waveguiding structure such as the circular waveguide 84. The amplified waves propagating through the plasma region 73 of the tube will radiate outwardly from the plasma region, as depicted by the inclined arrows, will couple into circular waveguide 84, and may propagate to a utilization device such as an antenna, for example. This demonstrates one of the advantages derived from the utilization of the transverse electrostatic waves near the multiple harmonics of the cyclotron frequency. That is, these waves have very high axial phase velocities and may directly couple into conventional transmission lines, thereby obviating the need for slow wave propagating and coupling circuits. Furthermore, because no special output coupling apparatus is needed,

the device of FIG. 7 may amplify to very high power levels without fear of power breakdown which is a common limitation in tubes that must employ special apparatus and circuits for coupling the amplified waves from the amplifier.

The above discussion has dealt with amplification that resulted from wave-wave interactions between selected beam and plasma transverse electrostatic waves having similar phase velocities. In accordance with the present invention, amplification of waves in the region of multiple harmonics of the cyclotron frequency also may be achieved by other phenomena which can be caused to occur within the beam-plasma system. A second type of amplification arises due to reactive instabilities that set-in in the beam-plasma system when the longitudinal dielectric constant of the plasma is less than zero ($K_p < 0$), in which case the plasma contributes inductive currents to the system and causes growth of the negative energy waves of the beam. Suitable output wave coupling means then is provided for coupling to the amplified negative energy beam waves to launch amplified electromagnetic waves in an external device or transmission line. The value of electron density of the warm plasma that will make $K_p < 0$ may be obtained by writing Equation 11 for the frequency ω approximately equal to

$$k_{\parallel}u + m\omega_c$$

in which all terms refer to the warm plasma, and solve for the minimum value of ω_p which causes the longitudinal dielectric constant to be less than zero. After taking into account the relative relationships between the plasmas parameters, the solution yields the following relationship for the plasma frequency ω_p , from which the plasma electron density may be derived,

$$k_{\parallel}u > 2\omega \left[\frac{k_{\parallel}u_t}{\omega_c} \right]^{1/2} \quad (13)$$

The value of the square root term may be quite small in practice so that in this expression there is substantially no restriction on the magnitude of $k_{\parallel}$. This indicates that what is desired in order to have a reactive instability far above the cyclotron frequency with a weak plasma is a very long axial wavelength, $\lambda_{\parallel}$, where $\lambda_{\parallel}$ is related to $k_{\parallel}$ by the expression

$$k_{\parallel} = \frac{2\pi}{\lambda_{\parallel}}$$

The value of plasma electron density required by Equation 13 is considerably smaller than would be required if the beam wave involved were a space charge wave as employed in the prior art that is exemplified by the device described in U.S. Patent 2,806,974, for example. The parameters of the beam of this device will be proportioned as indicated previously for the condition of stable negative energy transverse electrostatic waves at multiples of the cyclotron frequency.

Any of the previously described devices of FIGS. 5, 6 and 7 may be employed to achieve amplification by means of the reactive instability phenomenon just described so long as the conditions of Equation 13 are satisfied for the plasma.

It also will be appreciated that amplification may be achieved as a result of resistive instabilities which arise when the longitudinal dielectric constant of the warm plasma has a large imaginary value, that is, when the relationship $\omega - m\omega_c$ is approximately equal to $k_{\parallel}u_t$. With these conditions existing the negative energy transverse electrostatic beam waves at multiple cyclotron harmonic frequencies will be amplified, this being somewhat analogous to the resistive wall amplifier, but operable at higher frequencies than the prior art resistive wall amplifier whose operation is dependent upon amplification of short wavelength space charge waves as opposed to the long axial wavelength transverse electrostatic waves employed in the devices of this invention.

It should be understood that the above examples of the physical structures that may be employed in carrying out the present invention are merely representative of several ways of forming the required type of electron beam and for coupling to and from the transverse electrostatic waves in the beam-plasma system. Other arrangements and combinations of electron gun structures also may be employed and will function in accordance with the above teachings so long as the indicated requirements of both the beam and plasma parameters are satisfied.

In the above discussion certain critical relationships were set forth in order to assure that the transverse electrostatic waves will stably propagate on the beam and plasma, thus assuring reliable amplifier operation. It should also be understood that if it is desired to provide a signal source at the higher harmonics of the cyclotron frequency, the above development also will be instructed for this type of operation. As pointed out in connection with Equations 9 and 10, the electron density of the beam may exceed the relationships given in those equations so as to permit instabilities to arise on the beam, whereby the device then may function as a self-excited oscillatory source. Similarly, instabilities arising from the reactive and resistive nature of the plasma may be relied upon for the self-generation of the oscillatory signals within the device.

Although the above explanation of the interaction phenomena and the devices that have been described have dealt with electron beams in gas plasmas, the principles are applicable to other environments as well. That is, the fundamental requirement is that there be two bodies, or ensembles, of electrons. Therefore, the principles of this invention also may be applied to a double electron beam device, and to a photoconductive or doped semiconductor device through which an electron stream is passed.

While the invention has been described in its preferred embodiments, it is to be understood that the words which have been used are words of description rather than limitation and that changes within the purview of the appended claims may be made without departing from the true scope and spirit of the invention in its broader aspects.

What is claimed is:

1. Electron beam apparatus for providing output waves at a radian frequency ω comprising, input means to couple a signal to be amplified into said apparatus, means for producing a magnetic field β directed along an axis, means for producing a first ensemble of electrons having an axial drift velocity u and immersed in said magnetic field in a manner to cause the electrons of the ensemble to execute spiraling motions about axially directed flux lines of said magnetic field, the parameters of said beam and magnetic field β being proportioned to produce a transverse component of electron velocity which approximately satisfies the relationship

$$\frac{v_t^2}{u_t^2} 4m \frac{\omega^2}{\omega_b^2}$$

where v_t is the root mean square electron velocity in a direction transverse to said magnetic field and u_t is the root mean square thermal velocity of the electron parallel to said magnetic field, m is an integer, and ω_b is the radian plasma frequency of said electrons,

whereby said beam supports transverse electrostatic waves at said frequency ω near harmonic frequencies $m\omega_c$ of the cyclotron frequency ω_c of said electrons, the parameters of said first ensemble of electrons and said magnetic field β being further proportioned to approximately satisfy the relationship $\omega_b^2 > 8m\omega_c^2$, a second ensemble of electrons disposed in energy cou-

5

10

pling relationship with transverse electrostatic waves in said first ensemble of electrons, and means for extracting wave energy from transverse electrostatic waves supported by at least one of said ensembles.

2. The combination claimed in claim 1 wherein said second ensemble of electrons has an axial drift velocity u' and its parameters are proportioned with respect to said magnetic field β so that the following relationships are approximately satisfied

$$\frac{v_t^2}{u_t^2} > 4m \frac{\omega^2}{\omega_b^2}$$

15

and $\omega_p^2 < 8\omega_c^2$, where ω_p is the radian plasma frequency of the second ensemble and wherein the other quantities of said expression are as defined in claim 1 but relate to said second ensemble.

20

3. The combination claimed in claim 1 wherein the parameters of said second ensemble are proportioned to approximately satisfy the following relationship,

$$\omega_p > 2\omega \left(\frac{k_{\parallel} u_t}{\omega_c} \right)^{\frac{1}{2}}$$

25

where ω_p and ω_c are, respectively the radian plasma and cyclotron frequencies of the second ensemble, $k_{\parallel}$ is the parallel wave number of transverse electrostatic waves in said second ensemble, and u_t is the root mean square thermal velocity of second ensemble electrons in a direction parallel to said magnetic field, whereby said second ensemble presents an inductive reactance to said first ensemble.

30

4. An electron beam-gas plasma wave amplifying device comprising,

35

input means to couple a signal to be amplified into said apparatus, an ionizable gas medium contained within the enclosure, means for producing an electron beam that passes through said medium, means for producing a magnetic focusing field directly along an axis through said medium for immersing said beam and medium therein, said beam being comprised of electrons that have a component of their velocity in a direction transverse to said axis large enough to approximately satisfy the relationship

$$\frac{v_t^2}{u_t^2} > 4m \frac{\omega^2}{\omega_b^2}$$

40

where v_t is the root mean square velocity of the beam electrons in the direction transverse to said axis, u_t is the root mean square thermal velocity of the beam electrons in a direction parallel to the axis, m is an integer, ω is the radian frequency of waves to be amplified, and ω_b is the radian plasma frequency of the beam,

45

whereby said beam will propagate transverse electrostatic waves at a frequency near a harmonic frequency of the beam radian cyclotron frequency ω_c , said beam further being characterized by approximately satisfying the relationship $\omega_b^2 < 8\omega_c^2$ thereby to assure stable propagation of said transverse electrostatic beam waves,

50

means disposed adjacent said beam for supporting waves with transversely directed electric fields in wave coupling relationship with transverse electrostatic waves on said beam, and

55

output coupling means for coupling to transverse electric field waves in said device.

60

5. An electron beam-gas plasma device for providing output waves at a radian frequency ω comprising, input means to couple a signal to be amplified into said apparatus, an ionizable gas medium contained within an enclosure,

means for producing an electron beam that passes through said medium,
means for producing a magnetic focusing field directed along an axis through said medium for immersing said beam and medium therein,
said beam being comprised of electrons that have a component of their velocity in a direction transverse to said axis large enough to approximately satisfy the relationship

$$\frac{v_t^2}{u_t^2} > 4m \frac{\omega^2}{\omega_b^2}$$

where v_t is the root mean square velocity of the beam electrons in the direction transverse to said axis, u_t is the root mean square thermal velocity of the beam electrons in a direction parallel to the axis, m is an integer, ω is the radian frequency of output waves from said devices, and ω_b is the radian plasma frequency of the beam,
whereby said beam will propagate transverse electrostatic waves at a frequency near a harmonic frequency of the beam radian cyclotron frequency ω_c ,
means for ionizing said gas medium, and output coupling means adapted to couple to waves having transverse electrical field components for coupling waves from said device to external utilization means.

6. The combination claimed in claim 5 wherein the parameters of said gas medium when ionized are proportioned to approximately satisfy the relationship

$$\omega - m\omega_c > k_{||}u_t$$

where $k_{||}$ is the axial wave number of electrostatic waves at the frequency ω .

7. An electron beam-gas plasma wave amplifying device comprising,
an ionizable gas medium contained within an enclosure,
means for producing an electron beam that passes through said medium,
means for producing a magnetic focusing field directly along an axis through said medium for immersing said beam and medium therein,
said beam being comprised of electrons that have a component of their velocity in a direction transverse to said axis large enough to approximately satisfy the relationship

$$\frac{v_t^2}{u_t^2} > 4m \frac{\omega^2}{\omega_b^2}$$

where v_t is the root mean square velocity of the beam electrons in the direction transverse to said axis, u_t is the root mean square thermal velocity of the beam electrons in a direction parallel to the axis, m is an integer, ω is the radian frequency of waves to be amplified, and ω_b is the radian plasma frequency of the beam,
whereby said beam will propagate transverse electrostatic waves at a frequency near a harmonic frequency of the beam radian cyclotron frequency ω_c ,
said beam further being characterized by approximately satisfying the relationship $\omega_b^2 < 8\omega_c^2$ thereby to assure stable propagation of said transverse electrostatic beam waves,
means for ionizing said gas medium contained within said enclosure,
means for coupling input waves at a radian frequency ω near a frequency $m\omega_c$ into said device in a region proximate said beam and plasma,
said coupling means providing in said region trans-

10

15

20

25

30

40

45

50

55

60

70

versely-directed components of the electric field of said input waves.

8. The combination claimed in claim 7 wherein the parameters of said gas medium when ionized by approximately satisfying the relationship

$$\omega_p > 2\omega \left[\frac{k_{||}u_t}{\omega_c} \right]^{\frac{1}{2}}$$

where ω_p and ω_c are, respectively, the plasma and cyclotron frequencies of electrons of the ionized medium, $k_{||}$ is the parallel wave number of transverse electrostatic waves in the medium, and u_t is the root mean square thermal velocity of the electrons of the ionized media, whereby said ionized gas medium presents an inductive reactance to said electron beam.

9. An electron beam-gas plasma wave amplifying device comprising,

an ionizable gas medium contained within an enclosure,
means for producing an electron beam that passes through said medium,
means for producing a magnetic focusing field directed along an axis through said medium for immersing said beam and medium therein,
said beam being comprised of electrons that have a component of their velocity in a direction transverse to said axis large enough to approximately satisfy the relationship

$$\frac{v_t^2}{u_t^2} > 4m \frac{\omega^2}{\omega_b^2}$$

where v_t is the root mean square velocity of the beam electrons in the direction transverse to said axis, u_t is the root mean square thermal velocity of the beam electrons in a direction parallel to the axis, m is an integer, ω is the radian frequency of waves to be amplified, and ω_b is the radian plasma frequency of the beam,

whereby said beam will propagate transverse electrostatic waves at a frequency near a harmonic frequency of the beam radian cyclotron frequency ω_c ,
said beam further being characterized by approximately satisfying the relationship $\omega_b^2 < 8\omega_c^2$ thereby to assure stable propagation of said transverse electrostatic beam waves,

means for ionizing said gas medium and for establishing a plasma electron temperature that approximately satisfies the relationship

$$\omega - m\omega_c > k_{||}u_t$$

where $k_{||}$ is the axial wave number of waves at the frequency ω and $k_{||}$ and u_t now relate to plasma parameters,

means for coupling input waves at a radian frequency ω near a frequency $m\omega_c$ into said device in a region proximate said beam and plasma,
said coupling means providing in said region transversely directed components of the electric field of said input waves.
